GAME DEVICE

**Alfred E. Schinger, 410 Kenhorst Blvd.,
Reading, Pa. 19602**

Filed Apr. 7, 1965, Ser. No. 84,649

Term of patent 14 years

(Cl. D34—5)

FIG. 1.

FIG. 2.

FIG. 3.

FIGURE 1 is a top plan view of a game device showing my new design;

FIG. 2 is an elevational view thereof as seen by looking toward the lower end of FIG. 1; and

FIG. 3 is a bottom plan view thereof.

The top surface appearance of the design is characterized by contrasting areas and game designations as exemplified in FIG. 1.

The dominant features of my design reside in the portions shown in full lines.

I claim:

The ornamental design for a game device, substantially as shown and described.
